US00D939497S

(12) **United States Design Patent** (10) **Patent No.:** **US D939,497 S**
(45) **Date of Patent:** **** Dec. 28, 2021**

(54) **COMPUTER CASE**

(71) Applicant: **ADATA TECHNOLOGY CO., LTD.**,
New Taipei (TW)

(72) Inventors: **Chih-Chun Huang**, Taipei (TW);
Shun-Wen Chan, Taipei (TW)

(73) Assignee: **ADATA TECHNOLOGY CO., LTD.**,
New Taipei (TW)

(**) Term: **15 Years**

(21) Appl. No.: **29/698,841**

(22) Filed: **Jul. 19, 2019**

(30) **Foreign Application Priority Data**

May 24, 2019 (TW) 108303045

(51) **LOC (13) Cl.** **14-02**

(52) **U.S. Cl.**

USPC **D14/314**

(57) **CLAIM**

The ornamental design for a computer case, as shown and
described.

DESCRIPTION

FIG. 1 is a front perspective view of a computer case
showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, bottom and right side perspective view
thereof.

The broken lines depict portions of the computer case in
which the design is embodied that form no part of the
claimed design.

1 Claim, 8 Drawing Sheets
